APPARATUS AND METHOD FOR STARTING A VAPOR GENERATING POWER PLANT

Edward L. Kochey, Jr., Colebrook, Conn., assignor to Combustion Engineering, Inc., Windsor, Conn., a corporation of Delaware

Filed Nov. 20, 1962, Ser. No. 238,885
8 Claims. (Cl. 122—406)

The invention relates in general to a forced flow once-through vapor generating power plant, and more particularly to an improved apparatus and method for starting operation of the vapor, for instance, steam generator and turbine associated therewith.

It is known when starting up a forced flow once-through vapor generator to separate the vapor superheating and turbine portion from the vapor generating portion by a so-called boiler throttling valve. Such separation permits the use of auxiliary vapor in the superheater portion for the purpose of starting up the turbine, while the vapor generating portion at the same time is brought up to the desired temperature and pressure; or in other instances the fluid in the vapor generating portion after having been raised to a high pressure and temperature can be expanded through the boiler throttling valve to form a vapor and liquid mixture at lower pressure, with such vapor, after having been separated from the liquid in a vapor and liquid separator and superheated, then being used for starting up and rolling the turbine; or in still other instances, the temperature of the high pressure fluid can be raised to such a value that only dry vapor is produced when the fluid is expanded through the boiler throttling valve to the lower pressure, with such vapor then being superheated and utilized to heat and roll the turbine.

In employing these above-mentioned procedures, however, costly additional apparatus is required including vapor and liquid separating vessel and associated valves and piping, which equipment is only being used during start up and shut down operating periods. The considerable investment represented by this equipment is therefore not economically employed. Furthermore, during an initial phase of the start up procedures as hereinabove described, a turbine by-pass line must generally be made use of, such line leading from a point between the superheater and the turbine shutoff valve to a low pressure region, for instance the hot well of the condenser.

While the present invention still makes use of the boiler throttling valve, it discloses an improved apparatus and method for starting a forced flow once-through vapor generator which does not require start up apparatus such as separating vessel with associated valves and piping, nor does it make use of a turbine by-pass for raising the temperature of the vapor to a temperature suitable for rolling the turbine.

The objects of the present invention accordingly include an improved apparatus and method for starting a vapor generator of the forced flow once-through type with only vapor entering the finishing superheater; with such object being obtained without the use of auxiliary vapor for starting the turbine; without the use of a separating bottle or vessel and associated valves and piping; without the necessity of providing a turbine bypass for starting up purposes; and without the requirement of adhering closely to given pressure and temperature conditions in the vapor generating portion before the high pressure fluid in said portion can be expanded to the lower pressure prevailing in the vapor heating portion of the vapor generator, so that only vapor is produced therein.

Other objects and advantages will become apparent as the description of illustrative embodiments of the invention proceeds. The novel features which are considered characteristic of the invention are set forth with particu-

larity in the appended claims. These claims as well as the following description of the invention will best be understood when read in conjunction with the accompanying drawing in which:

5 FIG. 1 is a representation of a vapor power plant system in the form of a flow diagram incorporating one embodiment of the present invention as characterized by pressure differential means being provided for maintaining the liquid level in the convection superheater at a desired elevation.

10 FIG. 2 is a diagrammatic illustration of the pressure indicating means in the form of diaphragms.

15 FIG. 3 is a portion of a vapor power plant similar to that illustrated in FIG. 1, however, including mechanical means for indicating the liquid level in the convection superheater and maintaining said level at a desired location.

20 Referring now to the drawing in which like reference characters are used throughout to designate like elements the diagrammatic representation of FIG. 1 discloses a forced flow one-through vapor generator 10. A feed pump

25 12 is organized to supply working fluid to vapor generator 10 from a working fluid source 14 by way of conduit 16. To control or shut-off the flow of working fluid a feed valve 18 is provided in conduit 16. The working fluid passes serially through economizer 20, conduits 21 and 22, vapor generating tubes 24 lining the walls of furnace chamber 25, tubes 26, header 28, conduit 30, convection superheater 32, conduit 34, finishing vapor superheater 36 and conduit 38, to a point of use such as vapor turbine 40.

30 A valve 42 is provided in conduit 38 to shut off the flow of the working fluid to turbine 40. After having given up the major portion of its thermal energy in turbine 40 the working fluid vapor is condensed in condenser 14 and returned to the vapor generator via feed pump 12.

35 Fuel and air for combustion are supplied to vapor generator 10 by way of burner 44 in any conventional manner. The hot combustion gases produced by the burning of the fuel pass in heat exchange relation over the heat absorbing surfaces of the vapor generating tubes 24, final superheater 36, convection superheater 32 and economizer 20.

40 To maintain a minimum safe velocity in the vapor generating tubes 24 during start-up and low load operation a recirculating circuit 46 is provided for returning a portion of the fluid that is leaving header 28 for passage to convection superheater 32 through conduit 30, to the inlet of vapor generating tubes 24 by way of mixing vessel 48 and recirculating pump 50. A valve 52 permits control or stoppage of the flow of fluid recirculating through circuit 46. As an alternative to recirculation during start-up or low load operation, excess fluid can be discharged to waste through drain line 54 for the purpose of maintaining a minimum velocity in furnace tubes 24. To control flow through conduit 54 a boiler extraction valve 55 is provided.

45 As earlier mentioned hereinabove it has been found of advantage in starting up once-through vapor generators to make use of a shut-off and throttling device for separating the vapor generating portion 25 from the vapor superheating portion 32 and 36. In practice this device comprises a shut-off valve 56 and a throttling valve 57 arranged in bypass relation with valve 56. The purpose of bypass valve 57 is to obtain throttling with high pressure drop and small flow quantities, while the main shut-off valve 56 is designed for relatively low pressure drops and large flow quantities.

50 55 By employing boiler throttling valves 56 and 57 it is possible to commence start-up operation of the superheating and turbine portion without much delay after the start-up procedure for the vapor generating portion has begun. To accomplish this, however, superheated vapor must be furnished to the turbine by the finishing superheater 36 long before such vapor could be produced by the vapor generating tubes 24 at normal operating pressure and tem-

perature. Furthermore, while a large amount of heated gases are released in furnace chamber 25 for bringing the operating fluid up to operating pressure and temperature, the radiant heating surface of finishing superheater 36 must be protected from the heat of these gases during the final period of the start-up operation of the vapor generating section. Since it is undesirable to utilize operating fluid in the liquid state for this purpose vapor must be available for cooling the finishing superheater 36 long before the vapor generator is capable of furnishing such vapor at normal operating temperature and pressure.

In accordance with the invention this is accomplished by operating the primary or convection superheater 32 as a vapor generator, producing vapor at a pressure initially considerably lower than the pressure normally attained in the vapor generating portion 24 of the generator.

To maintain a desired liquid level 58 in the convection superheater 32 when operating it as a vapor generator during the start-up operating period a pressure differential indicating device 60 is employed to control the flow of high pressure fluid through throttling valve 57 by means of activator 62. As shown in FIGS. 1 and 2, device 60 is connected to pressure sensing means 64 and 66 each of which may take the form of a diaphragm transmitting the prevailing pressure hydraulically to pressure differential indicating device 60 in a well known conventional manner. Electric impulses could also be used to transmit pressure variations to device 60.

In FIG. 3 mechanical means including liquid column 67 and float 68 are shown for indicating the liquid level 58 and for conveying such indications to transmitter 70. Other conventional apparatus for indicating the location of the liquid level may be used in connection with the present invention.

According to the invention the start-up operation of the vapor generator includes the following steps:

With valves 56 and 57 closed, working fluid is pumped through economizer 20 and furnace tubes 24 and discharged through conduit 54 to a point of lower pressure. After this so-called clean-up operation, valve 55 is closed or set to open at a predetermined high pressure to allow for expansion of the fluid due to being heated. While the operating fluid is brought up to this pressure by the feed pump 12, firing of the furnace is commenced and continued until a predetermined temperature of the fluid is reached at a point such as at 72. During the heating of the fluid in tubes 24 recirculation of fluid is established through these tubes by means of recirculating pump 50, with the recirculated flow being such that a minimum safe velocity is always maintained in tubes 24. Obviously, but in a less economical manner such safe velocity could also be maintained by discharging a sufficient quantity of the working fluid by way of conduit 54 and valve 55.

The above mentioned predetermined fluid temperature measured at point 72 usually corresponds to a temperature of the combustion gases flowing over finishing superheater 36 at which it becomes unsafe to operate the unit without flowing a cooling medium such as vapor through the tubular heating surface of finishing superheater 36. Accordingly, at this point of the operating procedure valve 57 is gradually being opened permitting high pressure fluid to flow into convection superheater 32, with turbine valve 42 controlled to maintain a desired lower pressure therein. Pressure indicating devices 73 are provided to show the pressure drop across valves 56 and 57.

Because of the lower pressure prevailing in superheater 32 and 36 a portion of the high pressure fluid flashes into vapor with the remaining liquid establishing a liquid level 58. Convection superheater 32 accordingly now operates as a vapor generator absorbing heat from the combustion gases flowing thereover. The saturated vapor thus produced by flashing and evaporation flows into

finishing superheater 36 for cooling the tubes thereof and for being superheated therein.

After a suitable pressure and temperature has been reached in conduit 38 as indicated by pressure sensing device 74 and temperature sensing device 76 valve 42 is being opened to admit superheated vapor to turbine 40 for driving and heating of the same.

As the liquid in convection superheater 32 is being evaporated, superheated and conducted to the turbine additional fluid is being admitted by way of valve 57 in response to a lowering of the liquid level 58. As earlier described herein this can be accomplished by the pressure differential indicating device 60 receiving pressure impulses through diaphragms 64 and 66 as illustratively shown in FIG. 2, or receiving an indication of the liquid level elevation by means of float 68 and lever system 69 as shown in FIG. 3.

With turbine 40 thus being provided with a source of superheated vapor, while the temperature of the fluid in the vapor generating portion 25 is being raised to the normal temperature necessary for generation of vapor, a point in the start-up operation of the unit will eventually be reached when all of the liquid in the convection superheater 32 can be allowed to evaporate. The temporary function of superheater 32 of evaporating liquid is thereby gradually replaced by the normal function thereof of superheating the vapor. As the temperature in vapor generating portion 25 increases, a greater proportion of vapor is being produced by flashing, with the liquid level in superheater 32 receding to the vanishing point. Or, as the pressures in vapor generating portion 25 and superheating portions 32 and 36 approach equality, less and less of the total vapor is being produced by flashing and more and more by evaporation in tubes 24 as the liquid level in superheater 32 recedes to the vanishing point.

As soon as substantially equal pressures are established across valves 56 and 57 as observed by pressure sensing device 73 these valves will be fully opened and the vapor generator operated under normal operating conditions and control.

The present invention of a method and apparatus for starting up a once-through vapor generating power plant accordingly offers the following important advantages:

While heretofore it was deemed desirable if not essential to employ a vapor and liquid separating vessel with associated valves and piping between the boiler throttle valves 56, 57 and superheaters 32, 36, such auxiliary equipment is not required when starting up a once-through vapor generator in accordance with the teaching of the present invention.

While some start-up procedures as heretofore practiced required in lieu of a vapor and liquid separating vessel the adhering to very critical conditions of pressure and temperature of the fluid in the vapor generating section 25, before this fluid could be expanded through the boiler throttling valve 56, 57 so that only dry steam would result from such expansion, the present invention does not require adherence to such critical conditions of pressure and temperature.

While in the majority of start-up procedures of once-through forced flow vapor generators the use of a turbine by-pass is a dominating feature essential for successful start-up of the power plant, such turbine by-pass can be eliminated when starting up a power plant of the above-named type in accordance with the present invention.

While specific embodiments of the invention have been shown and described herein, it will be apparent to those skilled in the art that various changes, specifications, substitutions, additions and omissions may be made without departing from the spirit and scope of the invention as set forth in the appended claims.

What I claim is:

1. A method of starting a forced flow once-through vapor generator having a first heating section including vapor generating furnace walls and having a second heating section including a primary superheater and a finishing superheater said heating sections being directly connected and being serially arranged for flow of a vaporizable fluid therethrough; said method comprising the following steps:

- (1) maintaining a body of heated working fluid at a predetermined relatively high pressure in said first heating section;
- (2) flowing working fluid from said first heating section directly to said primary superheater, while reducing the pressure thereof from said high pressure down to a predetermined low pressure maintained in said primary superheater said low pressure being such that a partial flashing of said fluid into vapor occurs, so as to obtain a body of vaporizable fluid and a body of vapor, and establish a fluid level in said primary superheater;
- (3) generating additional vapor from said body of vaporizable fluid in said primary superheater and passing vapor to said finishing superheater for superheating therein;
- (4) conducting said superheated vapor to a point of use; and
- (5) controlling the flow of vaporizable fluid from said first heating section to said primary superheater to establish and maintain the fluid level in said primary superheater within desired limits.

2. A method of starting up a forced flow once-through steam generator having a tubular first heating section and having a tubular second heating section including a primary superheater and a finishing superheater said heating sections being directly connected and being serially arranged for flow of water and steam therethrough; said method comprising the following steps:

- (1) producing and maintaining a body of heated water at a predetermined supercritical pressure in said first heating section only;
- (2) flowing water from said first heating section directly to said primary superheater, while throttling it from said supercritical pressure down to a predetermined subcritical pressure maintained in said primary superheater and finishing superheater, said subcritical pressure being such that a partial flashing of water into steam occurs, so as to obtain water and steam in said primary superheater and steam only in said finishing superheater;
- (3) generating additional steam from said water in said primary superheater and passing steam to said finishing superheater for superheating therein;
- (4) conducting said superheated steam to a point of use; and
- (5) controlling the flow of water from said first heating section to said primary superheater to establish and maintain a water level in said primary superheater within desired limits, while the steam generated in said primary superheater passes to said finishing superheater and to said point of use.

3. A method of starting up a forced flow once-through vapor generator having a first heating section including vapor generating furnace walls and having a second heating section including a primary superheater and a finishing superheater said heating sections being directly connected and being serially arranged for flow of a vaporizable fluid therethrough; said method comprising the following steps:

- (1) maintaining a body of heated working fluid at a predetermined relatively high pressure in said first heating section;
- (2) recirculating said body of heated working fluid

75

from the outlet of said furnace walls directly to the inlet thereof;

- (3) flowing working fluid from said first heating section directly to said primary superheater, while reducing the pressure thereof from said high pressure down to a predetermined low pressure maintained in said primary superheater said low pressure being such that a partial flashing of said fluid into vapor occurs, so as to obtain a body of vaporizable fluid and a body of vapor, and establish a fluid level in said primary superheater;
- (4) generating additional vapor in said primary superheater and passing vapor to said finishing superheater for superheating therein;
- (5) conducting said superheated vapor to a point of use; and
- (6) controlling the flow of vaporizable fluid from said first heating section to said primary superheater to establish and maintain the fluid level in said primary superheater within desired limits.

4. A method of starting up a forced flow modified once-through vapor generator having a first heating section including vapor generating furnace walls and having a second heating section including a primary superheater and a finishing superheater said heating sections being directly connected and being serially arranged for flow of a vaporizable fluid therethrough; the invention comprising feeding vaporizable fluid to said first heating section only; heating said vaporizable fluid by supplying heat to said first and second heating sections; permitting a first overflow of heated vaporizable fluid from said first heating section to a point of lower pressure for fluid cleanup purposes; discontinuing the feeding of vaporizable fluid to said first section while recirculating said fluid from the outlet of said furnace walls directly to the inlet thereof to maintain the flow velocity in said furnace walls above a predetermined minimum velocity; discontinuing said first overflow and raising the pressure in said first heating section to a predetermined value in excess of that prevailing in said second heating section; permitting a second overflow from the relatively high pressure region of said furnace walls to the relatively low pressure region of said primary superheater said excess of pressure being such that a partial flashing of said fluid into vapor occurs, so as to obtain a body of vapor and a body of vaporizable fluid in said primary superheater and to establish a liquid level therein; generating vapor from said body of vaporizable fluid in said primary superheater and flowing said vapor from said primary superheater to said finishing for superheating therein; conducting said superheated vapor to a point of use; and re-establishing a controlled flow of vaporizable fluid to said steam generator consistent with the flow of vapor to said point of use.

5. In a forced flow once-through vapor generator having a first heating section and having a second heating section including a primary superheater having a bottom inlet and a top outlet and a finishing superheater said heating sections being directly connected and being serially arranged for flow of a vaporizable fluid therethrough; the combination comprising:

- (1) means for maintaining a body of heated vaporizable fluid at a predetermined relatively high pressure in said first heating section;
- (2) means for flowing water from said first heating section directly to the bottom inlet of said primary superheater;
- (3) means for throttling said fluid from said high pressure down to a relatively low pressure maintained in said primary superheater with said low pressure being such that a partial flashing of said fluid into vapor occurs, so as to obtain vapor and liquid and establish a liquid level in said primary superheater;
- (4) means for generating vapor in said primary superheater;

- (5) means for passing vapor from the top inlet of said primary superheater to said finishing superheater;
- (6) means for superheating said vapor;
- (7) means for conducting said superheated vapor to a point of use;
- (8) means for controlling the flow of fluid from said first heating section to said primary superheater so as to establish and maintain the liquid level in said primary superheater within desired limits; and
- (9) means for feeding vaporizable fluid to said first heating section in conformity with the flow of superheated vapor to said point of use.

6. In a forced flow modified once-through steam generator having a first heating section including steam generating furnace walls and having a second heating section including a primary superheater and a finishing superheater said heating sections being directly connected and being serially arranged for flow of water and steam therethrough; the combination comprising:

- means for maintaining a body of heated water at a predetermined supercritical pressure in said first heating section;
- means for recirculating heated water from the outlet of said furnace walls directly to the inlet thereof;
- means for flowing water from said first heating section directly to said primary superheater;
- means for throttling said water from said supercritical pressure down to the subcritical pressure maintained in said primary superheater said low pressure being such that a partial flashing of water into steam occurs, so as to obtain water and steam and establish a water level in said primary superheater;
- means for generating steam in said primary superheater;
- means for passing steam to said finishing superheater;
- means for superheating said steam;
- means for conducting said superheated steam to a point of use;
- means for controlling the flow of water from said first heating section to said primary superheater so as to establish and maintain the water level in said primary superheater within desired limits; and
- means for feeding water to said body of water in conformity with the flow of superheated steam to said point of use.

7. In a forced flow modified once-through steam generator having a first heating section including steam generating furnace walls, and having a second heating section including a primary superheater and a finishing superheater, said heating sections being serially arranged for flow of water and steam therethrough; the combination comprising valve means for shutting off flow from said first to said second heating section; means for feeding water to said first heating section; means for heating

said water by supplying a heating medium to said steam generator in heat exchange relation with the heating surfaces thereof including said furnace walls, a primary superheater and finishing superheater; relief valves means for limiting the pressure in said first heating section to a predetermined value and for permitting a first overflow of heated water due to expansion thereof from said first heating section to a point of lower pressure; shut-off means for discontinuing the feeding of water to said first section; means for recirculating said water from a point downstream of the outlet of said furnace walls to the inlet thereof to maintain a predetermined minimum flow velocity in said furnace walls; shut-off means for discontinuing said first overflow; throttling means for permitting a second overflow from the outlet of said furnace walls to said primary superheater and said finishing superheater, said second overflow means being organized for throttling said flow from a higher pressure in said first heating section to a lower pressure in said primary superheater for obtaining water and steam and a water level in said primary superheater and steam only in said finishing superheater; means for obtaining an indication of the water level in said primary superheater; means for controlling said flow into said primary superheater such as to maintain said water level at a desired elevation; means for superheating the steam received from said primary superheater in said finishing superheater and conduct it to a point of use; and means for re-establishing a flow of feedwater to said steam generator consistent with the flow of steam to said point of use.

8. The organization defined in claim 7 wherein said means for indicating the water level in said primary superheater and for maintaining the same at a desired elevation comprises means for obtaining a static pressure differential between the inlet and the outlet of said primary superheater and means for regulating the flow from said first heating section to said primary superheater in response to variations in said pressure differential.
